UNITED STATES PATENT OFFICE.

FRANKLIN D. CHASE, OF BERKELEY, CALIFORNIA.

FLUSHER BOX.

Application filed March 4, 1922. Serial No. 541,022.

To all whom it may concern:

Be it known that I, FRANKLIN D. CHASE, a citizen of the United States, residing at Berkeley, in the county of Alameda and State of California, have invented certain new and useful Improvements in Flusher Boxes, of which the following is a specification.

My invention is an improved flush tank for toilets which is simple in construction, eliminating the use of a flush valve, efficient in operation and inexpensive to manufacture.

Referring to the annexed drawing in which my invention is illustrated and which forms a part of this specification:

Figure 1 is a plan view of my flush tank.

Figure 2 is a cross section of my flush tank taken on line 2—2 of Figure 1.

Figure 3 is a vertical longitudinal section of my flush tank taken on line 3—3 of Figure 1, certain parts being omitted.

Figure 4 is a longitudinal section of the intake valve.

Figure 5 is an elevation of the intake valve controlling means in its valve releasing position.

Figure 6 is a view similar to Fig. 5 of said controlling means in position holding the intake valve closed.

In the drawing 1 indicates a rectangular flush tank casing, in which is journaled at its ends an elongated water receptacle 2 by means of journals 3 and 4 in the ends of said tank casing. The receptacle 2 is open at the top and a bar 5 extends across the top midway between the ends thereof. On the outer end of the receptacle journal 4 is secured a handle 6. An intake valve is mounted in and extends through the upper rear part of the left end wall of the casing 1 above the receptacle 2, said valve including a cylindrical valve casing 8 provided with an inlet 9 and an outlet 10, a valve seat 11 in its outer end, a valve closure member 12 adapted to engage said seat, a valve rod 13 threaded at its rear end on which said closure member screws, and a spring 14 surrounding said rod and bearing at its ends against a shoulder 15 in said casing 1 and a collar 16 on said rod. The inner end portion 17 of rod 13 is slightly enlarged in diameter and is reciprocatively mounted in a bearing 18 in the inner end of the casing 8. To the outer end of the casing 8 a water pipe 19 is

connected by means of a coupling 20. A horizontal bracket 21 is mounted at one end on the valve, a nut 22 being formed on said end of said bracket which screws on a thread 23 on the inner end of the valve casing 8. A lever 24 is pivoted at one end on the bracket 21 near the nut 22 and has a presser foot 25 on its pivoted end which engages the end of the portion 17 of the valve rod 13. The other end of the lever 24 extends through a guide 26 on the other end of the bracket 21 near the bar 5 into the path of movement of a catch 27 mounted on the upper edge of the bar 5 at the rear of the receptacle 2. A spring 28 is interposed between the lever 24 and a lug 29 on the bracket 21. A float lever 30 is pivoted to the end of the bracket 21 near the bar 5, which lever carries a float 31 on one end and has a cam 32 on its other end which rests in the path of movement of the end of lever 24 when the receptacle 2 is empty and the float is down. A water inlet pipe 33 is connected to the valve outlet 10 and extends to the center of the bottom of the receptacle 2 and carries on its lower end a cage 34 which prevents noise of the water passing from said pipe into said receptacle. A flush outlet pipe 35 leads from the bottom of the casing 1 and a sump 36 is formed in the bottom of the casing from which leads a drain conduit into the pipe 35.

Normally the receptacle 2 is full of water and rests lowermost but tipped backward slightly with the catch 27 in engagement with the end of lever 24, and the lever 24 swung back slightly under the influence of the spring 28 and spring 14 so that the presser foot 25 releases the end of the end portion 17 of valve rod 13 and the spring 14 holds the valve closure 12 on its seat 11, closing the valve, while the float 31 floats in its uppermost position holding the cam 32 under the end of the lever 24.

To flush the toilet the receptacle 2 is turned backwardly by the handle 6 and the water dumped therefrom into the tank casing 1 which passes out through pipe 35 into the toilet while the sump 36 is filled with water which passes slowly out of it through the drain conduit 37 into pipe 35 and into the toilet. The receptacle 2 is then swung forwardly by its handle into its lowermost position, during which operation the catch 27 engages the end of the lever 24 and swings

it forwardly until said end passes over the float arm cam 32 and engages the forward edge thereof as shown in Fig. 6, (the float being down because of the discharge of the 5 water from the receptacle 2), which movement of the lever 24 causes the presser foot 25 to engage the end portion 17 and press the valve closure 12 outwardly off its seat and open the valve 7, whereupon water 10 passes through said valve and the pipe 33 and cage 34 into the receptacle 2. As the receptacle 2 fills with water the float 31 rises and the lever 24 escapes the cam 32 and swings backwardly under the influence 15 of spring 28, and the spring 14, whereupon the presser foot 25 releases the part 17 and the valve closes and prevents water from entering the receptacle 2, while the receptacle 2 is tipped backwardly slightly by the engagement of lever 24 with catch 27 and is 20 again full of water in position to have the above described flushing operation repeated.

Having described my invention, I claim:

1. A flush tank including a flush tank casing having an outlet, a water receptacle journaled within said casing, an intake valve mounted in said casing for controlling the admission of water into said receptacle, a lever formed with a presser foot for engaging the end of the stem of said valve, a spring for swinging said lever so that said presser foot will release said valve stem, a

float lever, a float connected to said lever within said receptacle, a cam on said float lever, and a catch on said receptacle for engaging said lever and swinging it over said cam into engagement therewith into position so that said presser foot will open said valve, when the receptacle is swung back into normal position after being emptied, said cam being shaped to allow said lever to escape it when the float rises to cause said spring to swing said lever to release said presser foot from the valve stem to permit the valve to open. 35 40 45

2. A flush tank including a flush tank casing, a water receptacle journaled within said casing, a handle by means of which the water receptacle may be tilted, an intake valve for controlling the admission of water 50 into said receptacle, valve opening means, said means including a float, means for actuating said valve opening means to open said valve when the receptacle has been emptied and swung back into normal position, and means operated by the water rising in said receptacle to hold said valve opening means in its position to open said valve, and for releasing said valve opening means when the receptacle is filled to allow said valve to close. 55 60

In testimony whereof I affix my signature.

FRANKLIN D. CHASE.
